Application October 26, 1955, Serial No. 542,925

9 Claims. (Cl. 122—479)

This invention relates to apparatus for, and a method of, generating and superheating high pressure steam, wherein the temperature of the superheated steam is maintained at a predetermined value by gas recirculation.

The invention is exemplified in a steam generating and superheating unit involving a furnace, the walls of which include steam generating tubes in which at least a predominant portion of the total generated steam is generated as a result of radiant heat transmission from the furnace gases generated by a coal burning means operating at temperatures above the fusion temperature of the combustible in the coal. The heating gases pass from the furnace over a convection superheater, and a recirculated gas system withdraws lower temperature gases from a position in the gas stream beyond the superheater and introduces the gases into the furnace in increasing volume percentage-wise as the steam generating rate decreases. In the operation of such a unit, fused or semi-fused particles of slag, from the fuel, may accumulate upon the screen tubes and different sections of the convection heating means such as the superheater, and such accumulations may increase to such an extent that the draft loss through the furnace is materially increased. Under such circumstances the total draft resistance may be built up to such an extent that it exceeds the maximum static ability of the gas recirculating fan. When this occurs, the fan may be ruined within a few minutes because of the reverse flow of high temperature furnace gases through the fan. Additionally, there is apt to be a sudden increase in draft loss under conditions wherein the load suddenly changes from, for example, 50 percent load to 100 percent load when, at the same time, the amount of recirculated gas flow called for by the control system of the unit, approaches zero as the load approaches 100 percent load. The draft loss, generally speaking, varies as the square of the change in load, and under these circumstances that would mean that the draft loss is increased four times. This situation is apt to cause a reversal of flow of the recirculated gas through the fan and likewise increase the liability of ruining the fan in the manner above indicated. This invention involves a method of, and means for, preventing the above indicated type of damage to the fan without increasing the size of the fan or increasing the power requirements for operating the fan. According to the invention, when the recirculated gas flow to the furnace decreases to such an extent that the recirculated gas fan outlet static pressure approaches, to a predetermined degree, the gas pressure within the furnace, combustion supporting air is caused to flow to the fan inlet, this flow of air being controlled in such a manner that the minimum amount of fluid handled by the fan wheel does not drop below that required for the maximum static pressure peak of the fan. According to one embodiment of the invention a maximum flow of such air to the fan would occur at maximum boiler load when the flow of recirculated gases into the furnace is zero, and no air would flow to the fan at boiler loads requiring recirculated gas flow in excess of that delivered at fan static peak. The flow of air from the forced draft fan outlet through the recirculated gas

2

fan may, within the scope of the invention, be controlled manually or automatically.

The invention also involves a method of obtaining the above indicated results, wherein the fan static pressure is increased at low loads by the introduction of cool air or gas into the fan inlet, thus increasing the static of the fan. According to this method of the invention the cool air or gas flow into the fan inlet is modulated to control the temperature as required in order to give predetermined statics at low flow rates. One of the main advantages of using lower temperature air or gas dilution for temperature control is that the static remains high, whereas the motor horsepower falls off considerably.

The invention involves an increase in the flow of cold air from the forced draft fan of the unit into the inlet side of the recirculated gas fan as the flow rate of recirculated gas into the furnace decreases beyond a predetermined value, and it also provides means for protecting the fan by insulating the fan from gas or air connection with the furnace when the pressure differential between the fan outlet and the furnace falls below a predetermined amount, for example 1½" of water. In the practice of the invention pressure connections are added to the fan outlet and the furnace inlet to measure the pressure differential therebetween, the furnace inlet being restricted in such a manner that the predetermined resistance is achieved. As the pressure differential remains well above 1½" of water, the flow of recirculated gases to the furnace is automatically controlled or modulated from such variables as steam temperature and rate of vapor generation. As the pressure differential decreases and approaches 1½" of water, a damper is automatically opened to permit cold air from the forced draft fan to enter the recirculating fan inlet. The amount of this opening is adjusted as required to allow sufficient cold air to enter and lower the total temperature of the recirculating gas, thus maintaining a 1½" pressure differential between the recirculating fan outlet and the furnace inlet. The automatic system preferably operates so that, if the differential pressure continues to fall, which would be a sign that the furnace resistance is increasing, and the cold air damper reaches its wide open position so that no further margin may be gained then the system operates to render the fan motor inoperative. At the same time inlet and outlet dampers on the inlet and outlet sides of the fan are closed and cold air dampers upstream and downstream of the inlet and outlet dampers are opened so that the fan is blocked off or insulated from high temperature furnace gases by cold air. A second precaution involved in the automatic control system involves a temperature switch at the recirculating fan outlet. If the temperature rises in this outlet, which would indicate a reversal of flow of hot gases toward the fan, the motor is automatically stopped and the fan is automatically insulated as previously described. In addition to these features of the automatic system an alarm is also provided in this circuit which warns the operator that the furnace resistance is dangerously high when the pressure differential approaches 1½" water.

The invention will be concisely set forth in the claims, but for a complete understanding of the invention, its uses and advantages, recourse should be had to the following description which refers to a preferred embodiment illustrated in the accompanying drawings.

Of the drawings:

Fig. 1 is a diagrammatic representation of a gas recirculation system embodying the invention and associated with a vapor generating and superheating unit; and

Fig. 2 is a vertical sectional view of the vapor generating and superheating unit with which the gas recirculation system of Fig. 1 is associated.

In Fig. 1 there is diagrammatically illustrated a cyclone

furnace 20 burning a fuel of such characteristics that there would be a tendency to foul the associated heat absorbing surfaces. The furnace discharges high temperature furnace gases into a primary furnace chamber 22, from the lower part of which the gases flow upwardly as indicated at 24 into a vertically elongated secondary furnace chamber 25, the walls of which include steam generating tubes. This secondary furnace chamber, the succeeding convection section including the steam superheater, and the pertinent recirculated gas system for control of superheated steam temperature over a wide range of rate of vapor generation are constructed and arranged in the manner shown and described in the pending patent application Serial No. 278,872, filed on March 27, 1952, by P. H. Koch, now Patent No. 2,884,909 and belonging to the same assignee. As disclosed in said application and illustrated in Fig. 2, the products of combustion pass upwardly through the secondary furnace chamber 25 and over a secondary superheater 27 to a downflow convection gas pass 29, then successively contact a primary superheater 31 and an economizer 33, and then flow into a duct 35 leading to an airheater 37. In communication with the duct 35 is the inlet of a duct 28 of a heating gas recirculation system.

In the illustrative steam generating and superheating unit of Fig. 2 the elements of the superheater 27 are arranged as pendent superheater platens disposed within the vertically elongated secondary furnace chamber 25 receiving the combustion products from the cyclone furnace, the latter being an example of fuel burning means. Parts of the pendent superheater platens are disposed in a part of the secondary furnace chamber receiving combustion products including high temperature heating gases with particles of fused slag suspended therein. In the illustrative unit there is a recirculated gas system including a fan and duct work having its inlet downstream in a gas-flow sense from the superheater, and having its gas outlet in communication with the upper part of the primary furnace chamber 22. This gas recirculation system and its associated controls operate to maintain the temperature of the superheated steam at a predetermined value over a wide load range, and to accomplish this, the flow of recirculated gas to the primary furnace chamber is increased as the load decreases, in a lower part of the load range. The recirculated gas system also functions to decrease the ratio of furnace absorbed heat to the total heat absorbed in superheating the vapor, as the steam demand decreases, this action also involving an increase in a proportion of the total heat absorbed by the superheater.

Referring further to the system shown in Fig. 1 as being a part of such a unit as that shown in the above identified pending patent application, the recirculated gas system includes a recirculating gas fan 26, preferably operated by an appropriate electric motor and receiving partially cooled heating gases through the duct 28, the inlet of which is in communication with the gas flow of the unit at a position beyond the superheater. The outlet of the fan 26 is connected by the duct work components 30 and 32 to an outlet 34 communicating with the primary furnace chamber 22.

As the rate of steam demand decreases toward a low load value, and as the rate of firing of the cyclone furnace 20 is decreased the dampers 36, disposed in the duct work component 30 are open and controlled or modulated to increase the recirculated gas flow through the opening 34 into the primary furnace chamber 22. The dampers 36 may be operated throughout a wide load range by appropriate control mechanism including a damper operator 38 appropriately connected to the dampers 36 by linkage 40. The damper operator 38 is intended to respond to changes in pneumatic loading pressure in the control line 42 and the connected control line 44, leading from a controller 46 in which, or connected with which there are suitable and known control devices for varying the loading pressure in the lines 42 and 44 in response to the conjoint influences of a plurality of variables such

as load or rate of vapor generation, and superheated steam temperature.

The controls above referred to may be considered as the normal operative controls for maintaining final steam temperature substantially at a predetermined value and, in practice, these controls may be such as those shown and described in the pending application to Paul S. Dickey, Serial No. 260,357 and filed on December 7, 1951, or in the pending patent application of Charles S. Smith, Serial No. 199,406 filed on December 6, 1950, now abandoned, or appropriate gas recirculation control components such as those indicated in the patent application of Durham and Weaver, Serial No. 322,646 filed on November 26, 1952. All of these applications are assigned to the Babcock & Wilcox Company and/or its wholly owned subsidiary, The Bailey Meter Company.

In general, the pertinent normal operative controls of the flow of recirculated gas operate to increase the flow of recirculated gas as the vapor generating load decreases toward a predetermined low load, with a minimum flow of recirculated gas at a relatively high load value.

The type of unit with which the pertinent controls of recirculated gas flow are associated is one in which the fuel burning means such as the cyclone furnace 20 operates under a positive, or superatmospheric pressure created by such means as the forced draft fan 50, the outlet of which includes duct work 100 having air flow control dampers 101 and duct work 52 leading to the air inlet of an air heater from which the air flows by appropriate duct work to the air inlet of the fuel burning means 20. Thus there normally is a relatively high gas pressure at the position of the recirculated gas outlet 34 into the primary furnace chamber 22, which gas pressure must be overcome by the operation of the recirculated gas fan 26 in order for the recirculated gas to flow from the fan into the primary furnace chamber. In practice, it has been determined that there must be a pressure differential between the position H, or the outlet 34, of the recirculated gas system into the primary furnace chamber, and the position I adjacent the outlet of the fan 26 of a value of the order of 1½" of water, and to effectively utilize the actual pressure differential between these points the pressure differential controller F, or 54 has opposite sides of its diaphragm connected by the lines 56 and 58 to the outlet side of the fan 26, and to the upper part of the primary furnace chamber, respectively, at positions I and H, respectively. This pertinent pressure differential may be decreased by an increase in draft loss through the unit occasioned by abnormal slagging of the screen and various convection sections, or by a sudden increase in the rate of vapor generation. When due to such conditions, the pressure differential at F is decreased below the predetermined value, there is apt to be a reverse flow of the high temperature heating gases from the upper part of the primary furnace chamber 22 and through the duct components 32 and 30, and through the fan 26. Such a reverse flow of gases would ruin the fan within a matter of minutes to cause great economic or personal injury loss not only to operators of the electric generating station with which the steam generating unit is associated but also to the users of the power developed thereby. Such a contingency is prevented by the present invention.

As disclosed in the copending application of H. G. Stalkamp, Serial No. 542,926, filed October 26, 1955, when the differential pressure between the points I and H, measured by the differential pressure controller 54, approaches or drops below 1½" of water, which means that the recirculated gas flow is approaching a dangerous condition which might lead to reverse gas flow, the associated controls so change the pneumatic loading pressure in the line components 60—62 that the alarm M is sounded and, simultaneously as a result of the signaling of the relay J through the change in loading pressure in said line components, opens the damper A through the

agency of the damper operator A', sufficiently to permit such flow of cold air through the duct 102 and through the communicating duct 67 that the pressure differential between H and I is restored to a value well above $1\frac{1}{2}$ " of water. Simultaneously with the opening of the damper A, the damper D may be opened by the action of the damper operator D' in response to the same loading influence in the line components 60—62, as continued through the line component 70, the damper D being likewise closed after the pressure differential between the points H and I has been restored to a value well above $1\frac{1}{2}$ ".

If the differential pressure between the positions H and I continues to fall below 1½" of water while one or both of dampers A and D are wide open then the pressure switch K picks up the influence or impulse through the lines 60 and 74 from the relay J; and through the lines 72 and 74, turns off the fan motor switch 76; closes the dampers E through the intermediary of the damper operator 38 and its connections; closes the dampers C and opens the dampers B through the agency of the loading line 80, the control components 82 and 84, the line 86, the damper operator 88 and its connections 90-92; to insulate the fan 26 and permit the relatively high pressure cold air from the outlet of the forced draft fan 50 to flow through the duct components 100, 102 and 32 directly into the primary furnace chamber through the opening 34.

As an additional safety factor, if other controls fail, the temperature switch L, having the element 110 responsive to gas temperatures within the opening 34 or the upper part of the primary furnace chamber operates, upon a dangerous rise in temperature, through the agency of the loading line 112 to stop the fan motor, close dampers C and E and open the dampers B through their connections which are illustrated.

The dampers which are shown in the drawing are preferably arranged so that they may be alternatively, manually or automatically operated through the use of selector switches indicated in one of the above identified pending applications, and thus, for the isolation of the recirculating gas fan from high temperature furnace gases other than that above referred to the operator may manually open the dampers A and the dampers B to permit cold air to flow to the primary furnace and to the inlet side of the fan, and to close the dampers C and D, thus providing for bodies of cold air on both inlet and outlet sides of the fan, after the fan motor is stopped.

Whereas the invention has been described above with reference to a steam generating and superheating unit having a recirculated gas flow system functioning to maintain superheat at a predetermined temperature, and in doing so, to increase the recirculated gas flow from a condition in which there is no flow of recirculated gas at top load or control load (by the expression top load, the top load on the recirculated gas system is referred to rather than top load on the boiler) it is to be recognized that the invention should be considered as of such a scope as to cover the operation of a steam generating and superheating unit in which there may be appreciable flow of recirculated gas at top load on the boiler while that flow of recirculated gas may increase as indicated above as the rate of vapor generation approaches a minimum. It is also to be recognized that the invention is also applicable to the operation of steam generating and superheating units in which the introduced gases of lower temperature function in a gas tempering manner in which the flow of recirculated gases may increase as the boiler load increases. Obviously similar means may be employed to control the recirculated gas flow in the manner above indicated, regardless of the variation of the conditions mentioned immediately above.

Although the invention has been described with reference to a preferred embodiment thereof, it is to be

appreciated that the invention is not necessarily limited to all of the details of that embodiment. The invention is, rather, to be taken as of a scope commensurate with the scope of the sub-joined claims.

5. What is claimed is:

1. In a steam generating and superheating unit of the water tube type, wall means including steam generating tubes and defining a furnace chamber, means normally supplying said chamber with high temperature heating gases, said last named means including a fuel burner and a forced draft fan supplying air to the burner, a convection steam superheater subject to the gas flow from the furnace chamber, a recirculated gas system including a fan and connected ductwork normally withdrawing a percentage of the heating gases after loss of heat therefrom in the superheating and introducing the withdrawn gases into the furnace chamber, means to detect a change in gas pressure differential between the furnace chamber and the recirculated gas fan outlet, and means rendered effective when the pressure differential between the furnace chamber and the recirculated gas fan outlet falls below a predetermined value to provide for air flow from the forced draft fan through the recirculated gas fan and thereby restore said pressure differential to a value at least as high as said predetermined value, said last named means including dampered duct-work communicating with the outlet side of the forced draft fan and the inlet side of the recirculated gas fan.

2. In a steam generating and superheating unit of the water tube type, wall means including steam generating tubes and defining a furnace chamber, means normally supplying said chamber with high temperature heating gases, a convection steam superheater subject to the gas flow from the furnace chamber, a recirculated gas system including a fan and connected ductwork normally withdrawing a percentage of the heating gases after loss of heat therefrom in the superheating and introducing the withdrawn gases into the furnace chamber, means to detect a change in gas pressure differential between the furnace chamber and the recirculated gas fan outlet, and means rendered effective when the pressure differential between the furnace chamber and the recirculated gas fan outlet falls below a predetermined value to increase gas and air mixture flow through the recirculated gas fan and thereby restore said pressure differential to a value at least as high as said predetermined value, said last named means including means supplying the connecting ductwork of the recirculated gas fan with lower temperature air to effect such increase in flow of the gas and air mixture.

3. In a steam generating and superheating unit of the water tube type, wall means including steam generating tubes and defining a furnace chamber, means normally supplying said chamber with high temperature heating gases, a convection steam superheater subject to the gas flow from the furnace chamber, a recirculated gas system including a fan and connected ductwork normally withstanding a percentage of the heating gases after loss of heat therefrom in the superheating and introducing the withdrawn gases into the furnace chamber, fuel burning means firing the furnace chamber, an air heater, means supplying combustion supporting air to the air heater for subsequent flow to the fuel burning means, said last named means including a forced draft fan, ductwork connecting the outlet side of the forced draft fan ahead of the air heater and the inlet ductwork of the recirculated gas system, means to detect a change in gas pressure differential between the furnace chamber and the recirculated gas fan outlet, and means rendered effective when the pressure differential between the furnace chamber and the recirculated gas fan outlet falls below a predetermined value to increase the flow of gas and air mixture through the recirculated gas fan and thereby restore said pressure differential to a value at least as high as said predetermined value, said last named means

also decreasing the temperature of the total gas and air mixture flow through said recirculated gas fan.

4. In a vapor generating and superheating unit, wall means including vapor generating tubes normally receiving heat predominantly by radiant heat transfer from high temperature furnace gases within a furnace chamber formed by the wall means, fuel burning means in the form of a cyclone furnace supplying the furnace chamber with high temperature heating gases, a forced draft fan and associated ductwork normally supplying the cyclone furnace with super-atmospheric pressure combustion supporting air, a convection superheater including spaced tubes internally receiving the steam generated in said generating tubes and subject externally to the flow of said heating gases after loss of heat therefrom in the vapor generating zone, a recirculated gas system including a fan and fan inlet ductwork communicating with the heating gas flow downstream of the superheater and having fan outlet ductwork communicating with the furnace chamber, cold air ductwork having its inlet connected with the outlet side of the forced draft fan and having its outlet connected with the recirculated gas fan inlet ductwork, means to detect a change in gas pressure differential between the furnace chamber and the recirculated gas fan outlet, a damper in the cold air ductwork openable when the pressure differential between the recirculated gas fan outlet and the recirculated gas system outlet falls below a predetermined value to provide for sufficient flow of cold air to the fan inlet ductwork of the recirculated gas fan to establish said pressure differential at a value above said predetermined value.

5. In a high pressure steam generating and steam superheating unit, wall means including steam generating tubes and defining a furnace chamber normally receiving high temperature heating gases from which heat is predominantly radiantly transmitted to water within the tubes to generate steam, means including a fuel burner and a forced draft fan for supplying the furnace chamber with high temperature furnace gases, said last named means including forced draft fan ductwork communicating with the fuel burner, a superheater subject to flow of the gases from the furnace chamber and connected to the outlets of the steam generating tubes so as to superheat the generated steam predominantly by convection heat transfer, a gas recirculation system including a fan and fan inlet duct work communicating with the flow of heating gases downstream of the superheater and having fan outlet ductwork communicating with the furnace chamber, means rendered effective when the pressure differential between the furnace chamber and the recirculated gas fan outlet falls below a predetermined value to provide air flow from the forced draft fan through the recirculated gas fan and thereby restore said pressure differential to a value at least as high as said predetermined value, said last named means including an air duct having its inlet communicating with air flow from the forced draft fan and having its outlet communicating with the gas inlet side of the recirculated gas fan, and air flow control means in said air duct for permitting air flow into the recirculated gas fan inlet ductwork.

6. In a vapor generating and superheating unit having a fluid cooled furnace, means supplying heating gases to the furnace, a superheater subject to the heating gas flow after loss of heat therefrom in vapor generation, and a recirculated gas system including a fan having inlet and outlet ductwork associated therewith, the method of operation which comprises withdrawing heating gases through said inlet ductwork from a position downstream gas-wise of the superheater and discharging the withdrawn gases through said fan outlet ductwork into said furnace by establishing a pressure differential between the gases in the furnace and in the gas space at the outlet side of the gas fan, varying the percentage of the

heating gases so withdrawn, and increasing the static pressure of the fan in response to a decrease in said pressure differential below a predetermined value by introducing a gaseous fluid into the inlet of said fan at a temperature considerably less than the temperature of the gases flowing through said fan inlet ductwork to the gas fan to restore said pressure differential to a value at least as high as said predetermined value.

7. In a vapor generating and superheating unit, walls including fluid cooled tubes defining a furnace normally receiving high temperature heating gases, a superheater subject to the flow of gases from said furnace and connected for series flow of fluid from said tubes, a gas recirculation system including a gas fan, fan inlet ductwork communicating with the flow of heating gases downstream gas-wise of said superheater, and fan outlet ductwork communicating with said furnace, and means rendered effective when the pressure differential between the furnace and the gas fan outlet falls below a predetermined value to provide flow of a gaseous fluid into the inlet of said gas fan at a temperature considerably less than the temperature of the gases flowing through said fan inlet ductwork to the gas fan and thereby restore said pressure differential to a value at least as high as said predetermined value.

8. In a vapor generating and superheating unit, walls including fluid cooled tubes defining a furnace normally receiving high temperature heating gases, a superheater subject to the flow of gases from said furnace and connected for series flow of fluid from said tubes, a gas recirculation system including a gas fan, fan inlet ductwork communicating with the flow of heating gases downstream gas-wise of said superheater, and fan outlet ductwork communicating with said furnace, and means rendered effective when the pressure differential between the furnace and the gas fan outlet falls below a predetermined value to provide flow of air into the inlet of said gas fan at a temperature considerably less than the temperature of the gases flowing through said fan inlet ductwork to the gas fan and thereby restore said pressure differential to a value at least as high as said predetermined value, said last named means including a forced draft fan and a duct communicating with the outlet side of the forced draft fan and the gas fan inlet ductwork and thereby restore said pressure differential to a value at least as high as said predetermined value.

9. In a vapor generating and superheating unit, walls including fluid cooled tubes defining a furnace normally receiving high temperature heating gases, a superheater subject to the flow of gases from said furnace and connected for series flow of fluid from said tubes, a gas recirculation system including a gas fan, fan inlet ductwork communicating with the flow of heating gases downstream gas-wise of said superheater, and fan outlet ductwork communicating with said furnace, means for introducing air into the inlet of said gas fan at a temperature considerably less than the temperature of the gases flowing through said fan inlet ductwork to the gas fan, and means for isolating said gas fan from the heating gas flow and for cooling the inlet and outlet sides of the gas fan including dampers in said fan inlet and outlet ductwork, a forced draft fan, and ductwork communicating with the outlet side of the forced draft fan, the gas fan inlet ductwork upstream gas-wise of the dampers therein; and the gas fan outlet ductwork downstream gas-wise of the dampers therein.
